FABRIC HOLDER FOR MENDING AND
THE LIKE

Jessie A. Marshall, Boston, Mass.

Application January 4, 1939, Serial No. 249,213

3 Claims. (Cl. 223—100)

This invention relates to a device for holding portions of fabrics suitably stretched for mending, darning, embroidering or other equivalent operations.

It is an object of the invention to provide means for holding portions of fabrics firmly but without danger of injury to the fabric. It is a further object of the invention to hold the fabric in such a manner as to avoid undesirable distortion thereof. It is still another object of the invention to provide holding means which are adaptable to various shapes of fabric articles. As hereinafter described, the invention includes a light flexible ring having a smooth non-slip surface. Such rings can easily be carried in a purse or hand-bag and may be employed singly or in groups in any situation where other fabric holding and stretching means have been employed and in many situations where prior fabric holding means could not be successfully employed.

For a more complete understanding of the invention, reference may be had to a description of certain embodiments thereof which follows, and to the drawing of which

Figure 1 is a perspective view of a device embodying the invention, a portion being broken away.

Figure 2 is a section on the line 2—2 of Figure 1.

Figure 3 is a side elevation, partly in section, showing the device in use.

Figure 4 is a plan view of a modified form of the invention, in use.

Figure 5 is a sectional view of the device shown in Figure 4, in conjunction with parts of a sewing machine.

Figure 6 is a fragmentary elevation of an embodiment of the invention operatively located in the finger of a glove.

As indicated in Figures 1 and 2, the invention may be embodied in a single ring 10 which is flexible and which preferably consists of a helical coil 12 of spring wire with its ends permanently secured together to form a circular ring. This coil is covered by a substantial coating 14 of rubber or equivalent material, this rubber forming a continuous smooth coating on the exterior of the coil and extending into the interstices between successive turns of the coil. The coating may be conveniently applied by dipping the ring into a suitable liquid containing rubber, preferably a prepared latex mixture which is self-vulcanizing or prevulcanized. The rubber content of such a solution enters into and fills up

the interstitial spaces between the successive turns of the coil and adheres to the wire so that a strong coherent ring is thus formed. It is preferred that the turns of the coil be sufficiently close together to prevent any substantial ingress of the liquid into the hollow interior of the coil. The coating on the exterior is continuous and smooth. A number of successive immersions may be necessary to obtain the desired thickness and smoothness of the coating on the exterior of the coil.

When a single ring of this kind is used, it is preferred to employ therewith a shield which may consist of a semi-flexible disk 16 of suitable material such as bristol board, thin sheet Celluloid, or any other suitable equivalent. This disk is preferably circular as indicated in Figure 1 but may be made with an oval or other shape, it being desirable that the perimeter be approximately equal to the length of the coil forming the ring. While it is not necessary that the disk 16 be attached to the ring 10, it may conveniently be attached loosely thereto by a number of loops 18 of thread which pass through the disk and around the ring. The disk 16 acts as a guard to prevent the needle which is used to mend the fabric stretched over the ring from picking up portions of the fabric which are under the ring. Thus, as indicated in Figure 3, a piece of fabric such as a stocking may have a portion 20 stretched over the ring, adjacent portions 22 of the stocking being gathered beneath the ring and held by a rubber band 24 or other suitable tie. This leaves the hands of the operator free to hold the ring and the needle by which the mending or other operation is performed on the fabric. The shield 16 keeps the point of the needle away from the gathered portion 22 of the stocking beneath the ring so that there is no danger of sewing together portions of the stocking above and below the ring.

A plurality of rings may be employed in superposed position, if desired, alternate rings being inside and outside of the stocking or other fabric article to be mended or embroidered. It is preferred that the rings within the fabric be of slightly larger diameter than those outside of the fabric so that a sort of accordion form is produced, the fabric being very firmly held. This arrangement of larger and smaller rings is made possible by the flexibility of the rings whereby a larger ring may be thrust through smaller rings.

Rings of graded diameters may be employed in Figures 4 and 5 to stretch portions of a fabric

for mending, embroidering or stitching. As shown, a plurality of rings 30, 32 and 34 are arranged in nested relation, the rings being concentric and in a common plane. The diameters of the rings are preferably such as to allow a small clearance between the outside diameter of one ring and the inside diameter of the next larger ring to accommodate the fabric which is held by the rings. In order to hold the rings in proper relative positions as shown, a plurality of suitable spring clamps 40 may be provided, four such clamps being shown in Figure 4 engaging the tops and bottoms of the rings. It is understood that a larger or smaller number may also be employed if desired. These clamps may be of any convenient structure, a hinged type of clamp being illustrated. The fabric is stretched over the smallest ring 30, the next ring 32 being pressed against the opposite face of the fabric to hold the fabric in position on the ring 30. A third ring 34 may be employed, if desired, this ring being located as shown in Figure 5 and resulting in a more secure gripping of the fabric. The residual portion of the fabric is gathered around the stretched portion so as to be out of the way, particularly in case the mending is to be done by means of a sewing machine. If the material is comparatively sheer so that the gathered portion occupies little room, it may be gathered, as indicated in the left-hand portion of Figure 5, between the clamping jaws of the clamp 40. If preferred, the residual portion of the fabric may be held between or beyond the outer portions 42 of the clamps 40, as indicated at the right in Figure 5. This figure also illustrates a portion of the work platform 44 of a sewing machine together with a needle 46 and work-feeding element 48. It is evident that the holding device stretches the portion of the fabric to be mended or embroidered in a position which is advantageous for operation by a sewing machine.

The flexibility of the rings described is not only advantageous in mending stockings and the

like but also makes possible the use of the ring in small articles such as a finger 50 of a glove to hold the material of the fabric suitably stretched for convenient mending as indicated in Figure 6. A suitable shield (not shown), equivalent to the disk 16 but suitably shaped to enter the glove finger, may be employed with the ring 19 within the glove finger.

It is evident that the rings embodying the invention can be used in other advantageous ways. The embodiments of the invention herein described are by way of exemplification of the invention and not of limitation.

I claim:

1. A flexible ring for holding fabrics for mending and the like, comprising a helical coil of spring wire, the ends of said coil being secured together, and a substantial coating of rubber covering the exterior of the coil and adhering to the wire, said rubber extending into and filling the interstices between successive turns of the coil.

2. A device for holding fabrics for mending and the like, comprising a ring of helically coiled spring wire having a continuous coating of rubber covering the coil and filling the interstices between successive turns of the coil, a circular disk of semi-flexible sheet material having a diameter approximately equal to that of the ring, and means loosely attaching said disk to said ring to be concentric therewith.

3. A device for holding fabrics for mending and the like, comprising a ring of helically coiled spring wire having a continuous coating of rubber covering the coil and filling the interstices between successive turns of the coil, a circular disk of semi-flexible sheet material within said ring, and a plurality of loops of thread passing through said disk at spaced points near the perimeter and around adjacent portions of the ring to hold the disk loosely in place within the ring.

JESSIE A. MARSHALL.
